UNITED STATES PATENT OFFICE

135,905

DESIGN FOR A HEADSTOCK FOR LATHES

William M. McConnell, McKeesport, Pa., assignor
to Mackintosh-Hemphill Company, Pittsburgh,
Pa., a corporation of Delaware

Application August 21, 1942, Serial No. 107,986

Term of patent 14 years

To all whom it may concern:

Be it known that I, William M. McConnell, a citizen of the United States, residing in McKeesport, in the county of Allegheny and State of Pennsylvania, have invented a new, original, and ornamental Design for a Headstock for Lathes, of which the following is a specification, reference being had to the accompanying drawings forming a part thereof.

In the drawings:

Fig. I is a perspective view of a headstock, viewed from a position to the rear and to one side thereof, showing my new design.

Fig. II is a perspective view of the said headstock for lathes viewed from a position to the front of the headstock and to the same side thereof as in Fig. I.

Fig. III is a perspective view of the said headstock for lathes viewed from a position at the side opposite that shown in Figs. I and II and slightly to the rear of the headstock.

I claim:

The ornamental design for a headstock for lathes, substantially as shown.

WILLIAM M. McCONNELL.
